REINFORCED CONCRETE Cribbing

Filed April 25, 1931 2 Sheets-Sheet 2

UNITED STATES PATENT OFFICE

GEORGE E. NAGEL, OF COLUMBUS, OHIO

REINFORCED CONCRETE CRIBBING

Application filed April 25, 1931. Serial No. 532,930.

This invention relates to reenforced concrete cribbing designed primarily for use in constructing retaining walls, such as used in connection with hills and embankments of 5 railways, but it is to be understood that a cribbing in accordance with this invention may be employed for any purpose for which the same is found to be applicable.

The primary object of the invention is to 10 provide, in a manner as hereinafter set forth, a cribbing of the character aforesaid which includes a plurality of superposed header units which are mortised to receive therein end portions of stretchers extending between 15 the units, the stretchers being provided with reenforcing members extending substantially throughout their lengths and extending into the mortises of the header units, and the header units having continuous reenforcing 20 members extending around the mortises, thereby providing a construction wherein the pressure load of the filling is transmitted directly to the reenforcing members of the 25 header units to prevent any likelihood of shearing at the points of joinder between the header units and stretchers.

Other objects and advantages will be apparent from the following description, considered in connection with the accompanying 30 drawings, wherein:

Figure 1 is a perspective view of cribbing in accordance with this invention.

Figure 2 is a perspective view of one of the 35 front stretchers.

Figure 3 is a perspective view of one of the header units.

Figure 4 is a perspective view of one of the rear stretchers.

Figure 5 is a top plan of the cribbing.

Figure 6 is an enlarged section taken on the line 6—6 of Figure 5.

Figure 7 is a vertical section through one of the header units.

Figure 8 is a vertical section through one 45 of the front stretchers.

Figure 9 is a vertical section through one of the rear stretchers.

Referring to the drawings in detail, the 50 numeral 1 indicates the header units, each of which is of elongated construction substan-

tially triangular in cross section as more clearly shown in Figure 7. At each end thereof, each header unit 1 is provided with a head 2 of rectangular construction and of a width substantially equal to the base width of the 55 central portions of the header units. As shown in Figure 7, the heads 2 project materially beyond the triangular portions of the header units except at points adjacent the bases of the latter. The inner faces of the 60 heads 2 are formed with sloping shoulders 3 which merge into the peripheral faces of the central portions of the header units 1. Extending transversely through each head 2 is a mortise 4 having a vertical inner face 5, horizontal upper and lower faces 6, and an outwardly curved outer face 7. Each head 2 is provided on its upper face with a dowel 8 and is further provided in its lower face with a recess 9 corresponding in size and 70 contour to the dowel 8. When the headers 1 are arranged in assembled relation, the dowel 8 of one header unit is extended within the recess 9 of the unit next above.

The header units 1 are arranged in super- 75 posed relation to provide spaced stacks as shown in Figure 1, the units of the stacks being connected at their rearward ends by means of a plurality of rear stretchers 10 which correspond in number to the number of 80 header units in each stack. The rear stretchers 10 correspond in size and shape to the mortises 4 in the heads 2 with end portions of the stretchers 10 extending into the mortises. As shown in Figure 5, the rear stretchers 10 85 extend substantially halfway through the heads 2 and abut the end faces of similar rear stretchers 11 extending into the mortises of the heads at the opposite sides of the latter from the stretchers 10.

Embedded in each of the rear stretchers are a plurality of transverse reenforcing members, one of which is shown at 12 in Figure 9. Preferably six of the members 12 will be employed for each of the stretchers, the members 12 being suitably spaced lengthwise of the stretchers. Each reenforcing member 12 includes an arcuate central portion 13 merging at its ends into vertically disposed portions 14 which in turn merge into inclined 100

portions 15 which terminate in oppositely extending portions 16 arranged in parallel relation to the portions 14. Extending throughout the length of the stretchers are 5 a plurality of elongated reenforcing members 17, one of which extends through the arcuate portions 13 of the members 12, one through each of the portions 14 of the members 12, and one through each of the portions 10 16 of the members 12. End portions of the reenforcing members 17 project a material distance into the heads 2 of the header units 1.

Connecting the stacks of header units 1 at the forward ends of the latter are a plurality of front stretchers 18 which correspond in shape to the mortises 4 and are of materially greater height than the latter. Each of the stretchers 18 is formed at each 15 end thereof with a tenon 19 corresponding in size and shape to the mortises 4 for projection into the latter. Embedded in each front stretcher 18 and extending transversely thereof are a plurality of reenforcing members, one of which is shown at 20 in Figure 25 8. The reenforcing members 20 correspond in size and shape to the reenforcing members 12 embedded in the rear stretchers 10. Extending lengthwise of each front stretcher 30 18 and through the reenforcing members 20 are a plurality of elongated reenforcing members 21, and extending throughout the length of each front stretcher 18, in spaced relation to the inner face thereof, are a plurality of elongated reenforcing members 22. As shown in Figure 5, the tenons 19 extend substantially halfway through the heads 2 and abut the ends of similar tenons formed on similar stretchers 23 and extending into the mortises 4 at the opposite sides of the heads 2 from the stretchers 18. The reenforcing members 21 extend into the tenons 19. All except the two outermost ones of each group of the reenforcing members 22 also extend into the tenons 19.

Extending lengthwise through the header units 1 are a pair of spaced continuous reenforcing members 24 which extend in arcs around the mortises 4. The reenforcing members 24 are so arranged with respect to the side faces of the header units 1 that one of the members 24 will encircle the end portion of a rear stretcher 10 and the tenon 19 of a front stretcher 18, while the other reenforcing member 24 will extend around an end portion of a rear stretcher 11 and the tenon at one end of a front stretcher 23. The upper and lower stretchers of the members 24 are securely anchored with respect to each other by means of a plurality of reenforcing members, one of which is shown at 25 in Figure 7. Preferably six of the members 25 will be employed which are suitably spaced with respect to the length of the header units.

It will be apparent that any pressure of

the filling confined between adjacent stacks of the headers 1 and between the front stretchers 18 and rear stretchers 10 will be transmitted directly to the reenforcing members 24, 21, 22 and 17 owing to the extension of the 70 reenforcing members 17, 21 and 22 into the heads 2, and to the encircling relation of the reenforcing members 24 with respect to the reenforcing members 17, 21 and 22. Further 75 it will be apparent that the stretchers 18 provides the cribbing with a substantially closed face at the front of the fill. When the cribbing is used for relatively shallow fills, the rear stretchers 10 may be dispensed with since the dowels 8 of the heads 2 projecting into the 80 recesses 9 in the adjacent heads 2 will prevent any relative movement between the header units 1, thereby preventing displacement of the latter due to creeping or the like. Preferably the header units 1 will be seated on suitable base slabs as indicated at 26 in Figure 1. Owing to the cross sectional shape of the stretchers, the major volume of the concrete is in compression, thereby developing maximum beam strength with minimum volume. 90

It is thought that the may advantages of a cribbing in accordance with this invention will be readily apparent, and although the cribbing preferably will be constructed in accordance with the embodiments herein illustrated and described, it is to be understood that changes in the size, shape and arrangement of parts may be resorted to, so long as such changes fall within the scope of the invention as defined in the appended claims. 100

What I claim is:—

1. A cribbing comprising, a pair of stacks of superposed concrete header units, each of said units having a head at the front and rear thereof, said heads being provided with mortises extending transversely therethrough, and a stack of superposed stretchers having end portions thereof conforming in contour with and extending into said mortises, the walls of said mortises being endless and completely encompassing the end portions of said stretchers. 105

2. A cribbing comprising, a pair of superposed concrete header units, each of said units having a head at the front and rear thereof, said heads being provided with mortises extending transversely therethrough, a stack superposed front stretchers having end portions thereof conforming in contour with and extending into the mortises at the front end of the header units, a stack of superposed rear stretchers having end portions thereof conforming in contour with and extending into the mortises at the rear of the header units, the walls of said mortises being endless and completely encompassing the end portions of said stretchers, a plurality of elongated reenforcing members disposed lengthwise of the front and rear stretchers and 110

extending into said mortises, and a continuous reenforcing member disposed lengthwise of each header unit and extending around the mortises therein.

3. A cribbing comprising, a pair of superposed concrete header units, each of said units having a head at the front and rear thereof, said heads being provided with mortises extending transversely therethrough, a stack of superposed front stretchers having end portions thereof conforming in contour with and extending into the mortises at the front end of the header units, a stack of superposed rear stretchers having end portions thereof conforming in contour with and extending into the mortises at the rear of the header units, the walls of said mortises being endless and completely encompassing the end portions of said stretchers, a plurality of elongated reenforcing members disposed lengthwise of the front and rear stretchers and extending into said mortises, and a plurality of spaced reenforcing members embedded in each stretcher and extending transversely thereof and having the lengthwise disposed reenforcing members of the stretchers extending therethrough.

4. A cribbing comprising, a pair of stacks of superposed concrete header units, each of said units having a head at the front and rear thereof, said heads being provided with mortises extending transversely completely therethrough, the wall of each mortise being endless, a stack of superposed stretchers arranged transversely of the header units, and tenons formed on the ends of said stretchers, said tenons conforming in contour and extending into the mortises at one end of each stack of header units.

5. A cribbing comprising, a pair of stacks of superposed concrete header units, each of said units having a head at the front and rear thereof, said heads being provided with mortises extending transversely completely therethrough, the wall of each mortise being endless, a stack of superposed stretchers arranged transversely of the header units, tenons formed on the ends of said stretchers, said tenons conforming in contour and extending into the mortises at one end of each stack of header units, a plurality of spaced reenforcing members embedded in and extending transversely of each stretcher, and a plurality of reenforcing members disposed lengthwise of each stretcher, said lengthwise disposed reenforcing members extending through said transversely extending reenforcing members and into the tenons.

6. A cribbing comprising, a pair of stacks of superposed concrete header units, each of said units having a head at the front and rear thereof, said heads being provided with mortises extending transversely completely therethrough, the wall of each mortise being endless, a stack of superposed concrete rear

stretchers conforming in contour with the mortises at the rear of the header units and extending into such mortises, a stack of superposed concrete front stretchers formed on their ends with tenons conforming in contour with and extending into the mortises at the front ends of the header units, a plurality of reenforcing members disposed lengthwise of each front and rear stretcher, said reenforcing members extending into the mortises in the header units, a plurality of spaced reenforcing members embedded in and extending transversely of each front and rear stretcher, said lengthwise disposed reenforcing members extending through said transversely extending reenforcing members, and a continuous reenforcing member disposed lengthwise of each header unit and extending in an arc around the mortises therein.

7. A cribbing comprising, a pair of superposed concrete header units, each of said units having a head at the front and rear thereof, said heads being provided with mortises extending transversely completely therethrough, the wall of each mortise being endless, a stack of superposed front stretchers having end portions thereof conforming in contour with and extending into the mortises at the front end of the header units a stack of superposed rear stretches having end portions thereof conforming in contour with and extending into the mortises at the rear of the header units, a plurality of elongated reenforcing members disposed lengthwise of the front and rear stretchers and extending into said mortises, and a continuous reenforcing member embedded in each of said header units and extending around the mortises therein.

8. A header unit comprising, an elongated central portion substantially triangular in cross section and formed at each end thereof with a head, said heads being provided with mortises extending transversely completely therethrough, the wall of each mortise being endless, and a continuous reenforcing member embedded in the header unit lengthwise of the latter, common to and extending in arcs around the walls of said mortises.

9. A header unit comprising, an elongated central portion substantially triangular in cross section and formed at each end with a head, said heads being provided with mortises extending transversely therethrough, the wall of each mortise being endless, a pair of spaced endless reenforcing members embedded in the header unit lengthwise of the latter, common to and extending in arcs around the walls of said mortises, and a plurality of spaced reenforcing members embedded in the header unit and extending around said endless reenforcing members.

10. A stretcher comprising, an elongated concrete body portion, a plurality of spaced, sidewise opposed, apertured reenforcing

members embedded in the body portion transversely of the latter in proximity to its outer side face, and a plurality of elongated reenforcing members extending lengthwise of the body portion and through said transverse reenforcing members.

11. A stretcher comprising, an elongated concrete body portion having a tenon formed at each end thereof, a plurality of spaced, sidewise opposed, apertured reenforcing members embedded in the body portion and extending transversely of the latter in proximity to its outer side face, and a plurality of elongated reenforcing members extending lengthwise of the body portion through said transverse reenforcing members and into said tenons.

12. A stretcher comprising, an elongated concrete body portion, a plurality of spaced, sidewise opposed, apertured reenforcing members embedded in the body portion transversely of the latter in proximity to its outer side face, and a plurality of elongated reenforcing members extending lengthwise of the body portion and through said transverse reenforcing members, said body portion having its major cross sectional area disposed vertically and further having its outer face curved transversely.

13. A stretcher comprising, an elongated concrete body, a plurality of spaced flat, sidewise opposed, apertured reenforcing members embedded in the body and extending transversely of the latter in proximity to its outer side face, each of said members including a central portion, a pair of end portions and a pair of intermediate portions, said central portions being out of alignment with said intermediate portions transversely of the body, said central portions being out of alignment with said end portions transversely of the body, and a plurality of elongated reenforcing members extending lengthwise of the body, each of said lengthwise extending reenforcing members extending through one of said portions of each of said spaced reenforcing members.

14. A stretcher comprising, an elongated concrete body portion, a plurality of spaced, sidewise opposed, apertured reenforcing members embedded in said body portion transversely of and in proximity to the outer side face of the latter, a plurality of spaced elongated reenforcing members embedded in said body portion lengthwise of the latter and extending through said transversely disposed members, and a plurality of spaced elongated reenforcing members extending lengthwise of and arranged in proximity to the inner side face of said body portion.

15. A stretcher comprising, an elongated concrete body portion, a plurality of spaced, sidewise opposed, apertured reenforcing members embedded in said body portion transversely of and in proximity to the outer

side face of the latter, a plurality of spaced elongated reenforcing members embedded in said body portion lengthwise of the latter and extending through said transversely disposed members, a plurality of spaced elongated reenforcing members extending lengthwise of and arranged in proximity to the inner side face of said body portion, and said body portion having a squared inner side face and its outer side face curved transversely throughout.

16. In a cribbing, a pair of opposed spaced sets of superposed header units, each unit including a body part having an enlarged head at each end, the heads of each unit having oppositely disposed mortises extending transversely of and completely therethrough, the wall of each mortise being endless, a pair of spaced groups of stretchers, each group consisting of a series of endwise opposed sets of stretchers, each set comprising a series of superposed, spaced stretchers corresponding in number to the number of the header units of a set, the stretchers of each set having the cross sectional contour thereof corresponding to the shape of a mortise, and each pair of stretchers of each set having the opposed ends thereof seated in and completely encompassed by the wall of a single mortise.

17. In a cribbing, a pair of opposed spaced sets of superposed header units, each unit including a body part having an enlarged head at each end, the heads of each unit having oppositely disposed mortises extending transversely of and completely therethrough, the wall of each mortise being endless, a pair of spaced groups of stretchers, each group consisting of a series of endwise opposed sets of stretchers, each set comprising a series of superposed, spaced stretchers corresponding in number to the number of the header units of a set, the stretchers of each set having the cross sectional contour thereof corresponding to the shape of a mortise, and each pair of stretchers of each set having the opposed ends thereof seated in and completely encompassed by the wall of a single mortise, the stretchers of each set having their outer side faces curved transversely thereof throughout.

18. In a cribbing, a pair of opposed spaced sets of superposed header units, each unit including a body part having an enlarged head at each end, the heads of each unit having oppositely disposed mortises extending transversely of and completely therethrough, the wall of each mortise being endless, a pair of spaced groups of stretchers, each group consisting of a series of endwise opposed sets of stretchers, each set comprising a series of superposed, spaced stretchers corresponding in number to the number of the header units of a set, the stretchers of each set having the cross sectional contour thereof corresponding to the shape of a mortise, and each pair of stretchers of each set having the opposed ends thereof seated in and completely encompassed by the wall of a single mortise, the stretchers of each set having their outer side faces curved transversely thereof throughout.

of stretchers of each set having the opposed ends thereof seated in and completely encompassed by the wall of a single mortise, the cross sectional area of each of the stretchers of one group being less than the cross sectional area of each of the stretchers of the other group.

19. In a cribbing, a pair of opposed spaced sets of superposed header units, each unit including a body part having an enlarged head at each end, the heads of each unit having oppositely disposed mortises extending transversely of and completely therethrough, the wall of each mortise being endless, a pair of spaced groups of stretchers, each group consisting of a series of endwise opposed sets of stretchers, each set comprising a series of superposed, spaced stretchers corresponding in number to the number of the header units of a set, the stretchers of each set having the cross sectional contour thereof corresponding to the shape of a mortise, each pair of stretchers of each set having the opposed ends thereof seated in and completely encompassed by the wall of a single mortise, the stretchers of each set having their outer side faces curved transversely thereof throughout, and the stretchers of one group being oppositely disposed with respect to the stretchers of the other group.

20. In a cribbing, a pair of opposed spaced sets of superposed header units, each unit including a body part having an enlarged head at each end, the heads of each unit having oppositely disposed mortises extending transversely of and completely therethrough, the wall of each mortise being endless, a pair of spaced groups of stretchers, each group consisting of a series of endwise opposed sets of stretchers, each set comprising a series of superposed, spaced stretchers corresponding in number to the number of the header units of a set, the stretchers of each set having the cross sectional contour thereof corresponding to the shape of a mortise, each pair of stretchers of each set having the opposed ends thereof seated in and completely encompassed by the wall of a single mortise, and spaced endless reinforcing elements embedded in each header unit lengthwise thereof and surrounding the walls of the mortises in the heads of such unit.

21. In a cribbing, a pair of opposed spaced sets of superposed header units, each unit including a body part having an enlarged head at each end, the heads of each unit having oppositely disposed mortises extending transversely of and completely therethrough, the wall of each mortise being endless, a pair of spaced groups of stretchers, each group consisting of a series of endwise opposed sets of stretchers, each set comprising a series of superposed, spaced stretchers corresponding in number to the number of the header units of a set, the stretchers of each set having the

cross sectional contour thereof corresponding to the shape of a mortise, each pair of stretchers of each set having the opposed ends thereof seated in and completely encompassed by the wall of a single mortise, and the heads of the header units of each set having coacting means to prevent the shifting of an upper unit relatively to a lower unit.

22. In a cribbing, a header unit comprising a body part tapering from its bottom to its top and having a rounded top, a pair of heads of greater area in transverse section than the area of said body part in transverse section, means extended from the ends of the body part for coupling the heads to the latter, said heads being of rectangular form, each of said heads formed with a mortise extending completely therethrough transversely thereof, the wall of each mortise being endless and further being common to the opposed ends of a pair of stretchers extended into the mortise for completely encompassing such ends.

23. In a cribbing, a header unit comprising a body part tapering from its bottom to its top and having a rounded top, a pair of heads of greater area in transverse section than the area of said body part in transverse section, means extended from the ends of the body part for coupling the heads to the latter, said heads being of rectangular form, each of said heads formed with a mortise extending completely therethrough transversely thereof, the wall of each mortise being endless and further being common to the opposed ends of a pair of stretchers extended into the mortise for completely encompassing such ends, and reinforcing means embedded in the unit and extending around the walls of said mortises.

24. In a cribbing, a header unit comprising a body part tapering from its bottom to its top and having a rounded top, a pair of heads of greater area in transverse section than the area of said body part in transverse section, means extended from the ends of the body part for coupling the heads to the latter, said heads being of rectangular form, each of said heads formed with a mortise extending completely therethrough transversely thereof, the wall of each mortise being endless and further being common to the opposed ends of a pair of stretchers extended into the mortise for completely encompassing such ends, the mortise in one head being of less area than the mortise in the other head.

25. In a cribbing, a header unit comprising a body part tapering from its bottom to its top and having a rounded top, a pair of heads of greater area in transverse section than the area of said body part in transverse section, means extended from the ends of the body part for coupling the heads to the latter, said heads being of rectangular form, each of said heads formed with a mortise extending completely therethrough transversely thereof, the

wall of each mortise being endless and further being common to the opposed ends of a pair of stretchers extended into the mortise for completely encompassing such ends, and
5 reinforcing means embedded in the unit and extending around the walls of said mortises, the mortise in one head being of less area than the mortise in the other head.

In testimony whereof I affix my signature
10 hereto.

GEORGE E. NAGEL.
